UNITED STATES PATENT OFFICE.

JOHN N. ANDERSON, OF CHICAGO, ILLINOIS.

PHONOGRAPH.

1,389,089.

Specification of Letters Patent. Patented Aug. 30, 1921.

Application filed April 28, 1919. Serial No. 293,220.

To all whom it may concern:

Be it known that I, JOHN N. ANDERSON, a citizen of the United States, residing at Chicago, in the county of Cook and State of Illinois, have invented certain new and useful Improvements in Phonographs, of which the following is a specification.

This invention relates to phonographs.

One of the objects of the invention is to 10 provide an improved phonograph.

Another object is to provide a phonograph wherein access to the interior of the cabinet may be readily obtained.

Another object is to provide an improved 15 phonograph wherein access to the motor may be readily obtained.

Another object is to provide an improved phonograph wherein the horn is supported independently of the motor, turn-table and 20 tone-arm.

Other objects and advantages of the invention will appear from the specification and claims.

An embodiment of the invention is illustrated in the accompanying drawing, wherein—

Figure 1 is an elevation of the phonograph structure showing parts in section.

Fig. 2 is a transverse section taken on line 30 2—2 of Fig. 1.

Fig. 3 is a section taken on line 3—3 of Fig. 2.

Fig. 4 is a section taken on line 4—4 of Fig. 1.

35 In all the views the same reference characters are employed to indicate similar parts.

5 5 is a casing provided with the usual sound emitting opening 6, near its top open end, within which is placed a sound emitting 40 horn 7.

The upper smaller end of the horn 7 is connected to and supported by a horizontal board below the lid or top plate 8, hinged to the casing, as at 9, and supporting a suitable motor 10, which rotates a turn table 11. The cover 12 is also hinged to the casing near the point 9 and is held in its elevated position by suitable means 13. Immediately over the small end of the horn is a 45 tone arm 14, supported by lid 8 carrying the usual sound box 15. Extending across the interior of the casing, on all four sides, is a cleat 16 upon which rests the horn supporting board 17. The board 17 extends 50 from one side of the casing to the other and

rests upon the cleat 16 to which it is firmly affixed.

The horn proper is made, preferably, of four walls, of relatively thin wood, preferably spruce, providing a structure, preferably rectangular in shape. The small end of the horn is supported by the board 17, and on each side, the opposite walls 18 are glued to the blocks 19 and these blocks are secured to the board 17 by screws 21. A 60 block 20 is placed on the board 17 and its opening registers with the opening 20' covered by the tone arm 14. To the four walls 18 of the horn are glued, to the outside surfaces thereof, spaced apart strips or cleats 65 22, of wood, preferably, of the same material. The strips 22 are preferably beveled at their confronting edges and are not quite in contact with each other and therefore the reinforcing strips do not dampen the 70 vibrating effect of the walls of the horn, at the same time, they afford considerable 75 strength to withstand any mechanical vibration or jar.

The front end of the horn is suspended in 80 the opening 6, being supported entirely by the board 17, in the manner described, so that it may vibrate freely and bodily. The weight of the horn being suspended upon the board 17, exerts on the board a torsional 85 strain tending to turn the board on its longest axis and therefore the board contributes its resonant effect to that of the horn rather than to act as a damper to prevent its vibration.

90 The horn being supported independently of the hinged lid carrying the motor, turn-table and tone arm allows the lid to be raised readily for the inspection, cleaning and oiling of the motor and does not interfere with the ordinary automatic stop for stopping the motor when a record has been played. Such stops are usually operated by the tone arm and must ordinarily be folded or moved out of the way before the lid supporting the motor can be raised to give access to the motor and the interior of the cabinet. By having all of the operative parts carried by the lid, the stop may be 95 left in operative position without interfering with the raising of the lid.

100 While I have herein shown a single embodiment of my invention for the purpose of clear disclosure, it is manifest that many changes may be made in the general arrangement.

ment and configuration of the parts within the scope of the appended claims.

Having described my invention, what I claim is:—

- 5 1. In a phonograph a horn angular in cross section having a plurality of tapering walls of relatively thin material and spaced apart cleats secured to the outer surfaces of said walls at frequent intervals.
- 10 2. In a phonograph a horn angular in cross section having a plurality of tapering

walls of relatively thin material secured together at adjacent meeting edges, and spaced apart cleats secured to the outer surfaces of said walls at frequent intervals, adjacent cleats on the respective walls being in the same transverse plane leaving unoccupied spaces intervening between each series of cleats. 15

In testimony whereof I hereunto subscribe my name. 20

JOHN N. ANDERSON.
